UNITED STATES PATENT OFFICE

NORTON A. MEARS, OF CHICAGO, ILLINOIS, ASSIGNOR TO CHICAGO FORGING & MANUFACTURING COMPANY, OF CHICAGO, ILLINOIS, A CORPORATION OF ILLINOIS

HINGE

Application filed September 12, 1928. Serial No. 305,348.

This invention relates to a hinge. It has for one object to provide a hinge which may be used to support two covers for an opening. Another object is to provide a hinge of this type in which the covers may be raised separately or together. Another object is to provide a hinge of this general type in which all the parts are made of stampings or forgings and in which castings are eliminated, although I do not wish to be limited to the use of stampings or forgings, since under some circumstances it may be desirable to employ castings. Other objects will appear from time to time in the course of the specification and claims.

The invention is illustrated more or less diagrammatically in the accompanying drawings, wherein—

Figure 1 is a side elevation of the hinge, with the covers in section;

Figure 2 is a rear view;

Figure 3 is a view of the hinge looking from below;

Figure 4 is a view similar to Figure 1 showing a modified form;

Figure 5 is a rear view;

Figure 6 is a view looking from the bottom of the hinge support;

Figure 7 is a view generally similar to Figure 1 showing a further modification of the hinge;

Figure 8 is a view similar to Figure 3 showing the modified form of Figure 7;

Figure 9 is a perspective view of a hinge member.

A is a hinge plate. It is hinged adjacent its bottom as shown, and is provided with a narrowed and rearwardly curved portion A¹ adjacent its top. A² is a perforation formed in the part A¹. Adjacent the bottom of the plate A and extending laterally, preferably at right angles therefrom, is a ledge or extension A³. This is provided with perforations A⁴, A⁴.

The hinge base portion is formed generally

with an extended part B which has a perforation B¹ through it. This perforation may be squared as shown. Formed preferably integrally with the member B are two ears or upwardly extending parts B². These parts are bent towards each other as shown particularly in Figure 2 and form a bearing for the hinge plate A.

C is a journal extending through the upper end of the parts B² and through a perforation in the hinge plate A. By means of the member C the hinge plate is supported in the members B² for pivotal movement.

D is an upper cover member. It is provided preferably with a slot D¹ and a perforation D². The slot D¹ is shaped as shown to correspond to the shape of the portion A¹ of the hinge plate A. When the cover D is to be mounted, it is provided with one or more slots D¹ and a hinge is positioned in each one of them. A bolt D³ is passed through the perforation D² and through the perforations A² in each of the hinge members. The bolt thus serves to hold the cover and the hinge in supported and fixed relation with each other.

E is a second cover mounted below the cover D. It is provided preferably with one or more slots E¹. When this member is to be mounted it is positioned against one or more of the hinges so that the slots E¹ embrace the hinge plates A. Screws are then used, and passing through the perforations A⁴ in the plates A³, fasten the cover E to the hinge. There are thus provided two covers, each of which is separately supported from the hinge. These covers are so mounted that they may be moved together, in which case the hinge plates of the two covers pivot together about the journals C. The lower cover may be left in position and the upper cover D moved separately, in which case the cover pivots about the bolt D³.

The modified form shown in Figures 4, 5 and 6 is generally the same as that shown in Figures 1, 2 and 3 except that the ledge

A^3 is omitted. In its stead, one or more locking lugs or points F are provided. These points F penetrate into the wood or other material of the cover E and serve to position the parts and hold them together against slipping.

In the form shown in Figures 4, 5 and 6, in addition to the change just mentioned, is an additional hole G formed in the hinge 10 plate A and a perforation G^1 is formed in the cover E . This perforation, when the parts are assembled in the position shown in Figures 4 and 6, is in register with the perforation G in the hinge plate A . Thus a bolt 15 G^2 may be run through the perforation G^1 and it will pass through the perforations G in the several hinge plates A and thus it holds them in proper position with relation to the cover.

20 Instead of using a single bolt G^2 , two screws might be used or two bolts.

Although I have shown an operative device, it will be obvious that many changes might be made in the size, shape, number, 25 relation and distribution of parts without departing materially from the spirit of my invention, and I wish therefore that my showing to be considered as in a large measure dia- 30 grammatic. For example, although the type of hinge shown is adaptable for manufacture from sheet metal, stampings, forgings, and the like, I do not wish to be limited to such method of manufacture and wish it understood that my claims should be interpreted 35 to cover any hinge, regardless of the material or manner of making, which falls within in the terms of any claim or claims herein.

In Figure 7 I have shown a further modified 40 form in which the base plate of the hinge is turned under the cover and therefore it is practically concealed by the cover.

The use and operation of this invention are as follows:

Hinges of the type shown in the several 45 figures may be used in any association where it is desirable to have a hinge which will support two covers. One hinge alone may be used or several may be used in association. It is not essential that two be used as shown 50 in the examples herewith. For most purposes more than two would not be needed.

The several parts of the hinge are made of sheet metal stampings. The parts are of course separately made. They are then assembled, the moving part of the hinge being attached to the base part by a rivet or other suitable attachment. When the hinge is to be used, the covers may be fastened to each other in the form shown in Figures 1 to 3 60 inclusive. The lower cover is fastened to the hinge by being screwed to the lateral flange A^3 of the moving part of the hinge. The upper cover is slotted to receive the part A^1 . The hinge being in position with respect to the covers, the upper cover is fas-

tened by means of the long bolt D^3 or any other suitable attaching means might be used, but this method forms a strengthening and reinforcing part across the back of the cover and serves to fasten the hinge in place. In the form shown in Figures 4 to 6 inclusive, the moving part of the hinge does not have any laterally extending flange. The lower cover is slotted to receive the hinge and the hinge is driven into this slot so that its points project into the material of the cover. The one or more hinges which are to be fastened to the lower cover are fastened either by a short bolt for each hinge, or by a long bolt as shown. The upper cover may be slotted as shown in Figures 1 to 3, inclusive or the hinges may be attached at the ends of the cover as shown particularly in Figures 4 and 5.

The points F on the member A as shown in the modified form of Figure 4 may be driven directly into the wood. It is not necessary to cut or form recesses for them. A slot is made in the cover into which the body A of the hinge may fit and the points F are driven directly into the material of the cover.

I claim:

1. In a hinge and cover assembly, a cover member provided with a slot extending through the body of the cover and intersecting the upper and lower horizontal faces and the rear vertical face thereof, a hinge leaf secured within said slot and having portions extending beyond the confines of the body of the cover, one of said portions extending above the upper horizontal face of the cover and another of said portions extending rearwardly beyond the vertical face of the cover, said extended portions each being provided with a pivot receiving aperture located beyond the confines of the body of the cover, a second cover member having its rear edge slotted and pivotally connected to the upper extremity of the hinge leaf with the extremity of the leaf housed within the slot and a hinge base pivotally connected to the rearwardly directed extremity of the leaf and arranged for attachment to a supporting abutment.

2. In a hinge and cover assembly, a cover member provided with a vertical slot extending through the body of the cover and intersecting the upper and lower horizontal faces and the rear vertical face thereof, a leaf comprising a substantially flat metal plate mounted within the slot and having portions extending beyond the confines of the body, one of said portions extending above the upper horizontal face of the cover member and another of said portions extending rearwardly beyond the rear vertical face of the cover member, said extended portions being provided with pivot receiving apertures located beyond the confines of the cover, the body of the leaf and said extended portions

being confined to a single substantially vertical plane, a second cover member having its rear edge slotted and pivotally connected to the upper exposed extremity of the hinge leaf with the upper end of the leaf housed within the slot, and a hinge base provided with upstanding apertured lugs pivotally connected to the exposed rearwardly directed extremity of the hinge leaf and arranged for 5 securing to a supporting abutment.

10 Signed at Chicago, county of Cook and State of Illinois, this 31st day of August, 1928.

NORTON A. MEARS.
